DESIGN FOR A WHEELED VEHICLE

Henry M. Kinslow, Pasadena, Calif.

Application February 26, 1946, Serial No. 126,933

Term of patent 14 years

(Cl. D34—15)

To all whom it may concern:

Be it known that I, Henry M. Kinslow, a citizen of the United States, residing in the city of Pasadena, county of Los Angeles, and State of California, have invented a new, original, and ornamental Design for a Wheeled Vehicle, of which the following is a specification, reference being had to the accompanying drawing, forming a part thereof.

The figure of the drawing is a perspective view of the wheeled vehicle showing my new design.

I claim:

The ornamental design for a wheeled vehicle, as shown.

HENRY M. KINSLOW.
